UNITED STATES PATENT OFFICE.

HENRY L. F. TREBERT, OF ROCHESTER, NEW YORK.

VALVE MECHANISM.

1,145,631.

Specification of Letters Patent.

Patented July 6, 1915.

Application filed January 30, 1909. Serial No. 475,227.

To all whom it may concern:

Be it known that I, HENRY L. F. TREBERT, of Rochester, in the county of Monroe and State of New York, have invented certain new and useful Improvements in Valve Mechanism; and I do hereby declare the following to be a full, clear, and exact description of the same, reference being had to the accompanying drawings, forming a part of this specification, and to the reference-numerals marked thereon.

My present invention relates to engines and it has for its object to provide a simple, efficient and durable valve mechanism particularly adapted to internal combustion engines.

My improvements are further directed toward rendering the valve mechanism conveniently though not exclusively applicable to multiple cylinder engines, the improvements operating to reduce the cost and labor of production and at the same time furnish a strong and well balanced mechanism.

To these and other ends the invention consists in certain improvements and combinations of parts all as will be hereinafter more fully described, the novel features being pointed out in the claims at the end of the specification.

In the drawings: Figure 1 is a vertical central section of one cylinder of a multiple cylinder engine constructed in accordance with and illustrating one embodiment of my invention, the said section being taken transversely to the crank or engine shaft; Fig. 2 is a side elevation of the working parts of the engine as disclosed by a section taken through the crank-case valve seats and cylinders in planes parallel with the engine shaft; Fig. 3 is a top plan view of the valve controlling members in detail, the valve stems being shown in horizontal section; Fig. 4 is a detail, partly in section of one valve stem.

Like reference numerals in the several views indicate similar parts.

I have illustrated in the present instance the two end cylinders only of the multiple cylinder engine, the others being broken away, but being the same for the purposes of this specification as those shown, the cylinders 1 being preferably cast in pairs and mounted over openings 2 in the crank-case 3 through which openings operate the connecting rods 4 connected to the pistons 5 and to the crank shaft 6, as usual, the latter being preferably

journaled in the crank-case as at 7. The crank-case can be conveniently made in halves of two castings divided along the line indicated by 8 but extending together throughout all of the cylinders, but for the purposes of my invention I prefer to construct them with a plurality of partition members 9 which divide the crank-case into compartments 10, one for the crank 11 of each cylinder.

The cylinders are provided with water jackets 12 preferably in communication with each other, the water passages therein being indicated by W in the drawings and any suitable means being employed to maintain a circulation. The section through the valve seats in Fig. 2 is taken on the exhaust side of the engine and through the exhaust ports indicated by 13, but the intake ports are in all respects the same in the present engine, the latter being symmetrical in this respect. Continuations of these ports or passages 13 form the exhaust passages 14 which preferably intersect each other and preferably lead into a common exhaust pipe and the valve seats 15 are, in the present arrangement, situated in these passages, the pairs of valves, each pair comprising intake and exhaust, for each cylinder, being arranged on opposite sides of but adjacent to the plane of the partition 9 separating the crank chambers of the two cylinders. The valves 16 co-operating with the seats 15 are provided with stems 17 that operate in continuous bores or bearings 18 that preferably run parallel with and longitudinally of the cylinders 1 and are formed in portions 19 of the cylinder casting, the said bores terminating at one end adjacent the seats 15 and opening at their lower ends at 20 into the crank-case. It will thus be seen that as the water circulates freely around the portions 19 in which the valve stems are arranged and also about the exhaust passages 14, the valves and connected parts are kept reasonably cool which makes them durable, prolongs the period of their initial accurate adjustment and prevents the lubricating medium which is introduced in a manner to be described from being burned up on their stems.

The valve stems 17 of each cylinder project from the open ends 20 of the bores 18 to extend in parallelism upon opposite sides of the crank shaft 6 and through guiding bosses 20^a adjacent to the partition 9, the

said stems being provided with abutments 21 between which and the top of the crank-case are interposed springs 22 that normally hold the valves upon their seats. 5 Pivoted on a stud 23, rigidly mounted in the partition 9 at a point between the two valve stems of each cylinder, are a pair of valve controlling members 24 in the present form of diverging rock arms having shoulders 25 upon which the respective valve stems 17 rest forming an operative connection between the valves and arms, the former being pressed against the latter by the spring 22. The arms also have bearing portions 26 carrying rollers 27, 27^a.

Arranged below the crank shaft 6, that is on the opposite side of the latter from that of the cylinders, but preferably in the plane common to the axis of the crank shaft and 20 of the cylinder, is a cam shaft 28 journaled in the crank-case near the bottom thereof, as at 29, and in the partitions 9 to extend preferably continuously through all of the compartments 10, being driven by intermeshing 25 gears 30 and 31 on the cam shaft and crank shaft, respectively. The said cam shaft carries a cam 32 which revolves between the rock arms 24 and operates them successively by an engagement with the rollers 27, 27^a, 30 each vibration of an arm 24 through this action of the cam operating to lift one of the valves 16 by a reciprocation of its stem. The pivoted inner ends of the rock arms 24 are cut away along complimentary lines to 35 fit within each other, as shown in Fig. 3, to bring them both in the plane of the valve stems 17.

As the exhaust valve of the engine is generally designed to open to a greater extent 40 than the intake valve, a greater throw must be given to one valve stem than to the other. Then again it is often desired, for special work, to permanently reverse the normal direction of the engine, that is, design it for 45 a motion of the crank shaft in a reverse direction from that in which they are ordinarily arranged to rotate, in which case in the present engine the exhaust valves are made to control the intake, and the intake valves 50 the exhaust. To effect these ends I form the rock arms 24 in such a manner that the distances between their common pivot or axis 23 and the point on each arm at which they are operatively connected to the valve stems, 55 namely the shoulders 25, are equal, so that the said rock arms or valve controlling members are interchangeable on the stud 23, but I make the distance between the axis of one arm and the point of contact of the cam 32 or the point at which, through the principles of leverage, the said contact becomes effective, (which, in the present instance, is the center of the rollers 27, 27^a) 60 greater on one arm than on the other, where- 65 by each arm though operated to the same de-

gree by the cam 32 communicates a different degree of movement of its respective valve from that communicated by the other, the principle being that of two bell crank levers having two corresponding arms equal and the other two of unequal lengths. The cam 70 32 is also made symmetrical in design, as shown, that is in such manner that it will present the same cam surface when rotated in either direction and when located, as in 75 the present instance, between the rollers 27, 27^a of the two arms 24 it will actuate each valve controlling member to the same degree and in the same manner in whichever direction it is turning except that, with no change 80 in the rock arms, it will do so in reverse succession, the interval of time between their actuations, however, being the same.

Therefore in order to produce a left hand engine as an exception to a normal output 85 of right hand engines the manufacturer is not obliged to use any parts other than those used in the right hand engine, nor to change the stock parts, nor to change the positions of the cams, nor to turn the cam shaft end 90 for end as is commonly done. He has simply to interchange the arms 24 on their pivots putting one in the place of the other and feed his fuel to what would ordinarily be the exhaust port, starting his engine in 95 the reverse direction, whereupon the movement of the valves will be reversed, yet the timing retained as before, all with no additional labor or expense as it is manifestly just as easy to assemble the parts one way as 100 the other. As illustrated, the rollers 27, 27^a travel the same path in succession of each other on the cam but by widening the cam face they could travel in parallel paths with 105 the levers pivoted side by side and various other modifications, as is apparent might be made without departing from the spirit of my improvements, but it is essential to one branch of my invention that they traverse the same cam surface whether they follow 110 in each other's path or not.

Because of the fact that, as previously described, the projecting ends of the valve stems 17 of the pairs of valves of each of the adjacent cylinders are arranged upon opposite sides of the same crank-case partition 9, I am enabled, as shown in Fig. 2, to pivot the pairs of valve controlling members 24 for the valves of each cylinder upon opposite ends of the same stud shaft 23, supported in 115 the partition, out of the way of the cranks 11 and the cams 32 on the cam shaft are thus brought necessarily very close to the bearing of the latter in the partition 9, producing a rigid construction that will permit no appreciable give to the shaft and consequent inaccuracy in the seating of the valves even though the said shaft be made relatively light.

As previously stated the cam shaft is ar- 120

ranged very close to the bottom of the crank case which offers convenience to the mounting of a suitable rotary pump 33 thereon having an intake extension 34 extending to the bottom of the crank case as the latter may be filled with oil as a reservoir for the system. The pump may be of any suitable construction, the details thereof being immaterial to this invention, but preferably feeds to a supply pipe 35 common to all the cylinders and passing through the several crank case compartments thereof, within each of which is arranged a nozzle 36 at a proper inclination to emit a continuous or intermittent jet of oil in the direction of the cylinder, the jet being arranged to impinge upon a suitable surface of the engine interior that will cause it to break up and spray particles of oil for the lubrication of the piston bearings and other interior working parts, its result being similar to but more positive than an ordinary splash feed system. Some of this oil so distributed finds its way to the projecting ends of the valve stems 17 and to the openings 20 of the bores 18 in which they are arranged, whereat, with the constant reciprocation of the stems the oil is fed and drawn by capillary attraction up through the bores toward the valve seats, lubricating the stems throughout their length and being prevented in a great measure from clogging or gumming because of the heat by the cooling agency within the jackets 12 as previously pointed out.

35 Returning again to the valve controlling members 24, it will be noted that in the present instance the roller 27^a on the rock arm for the exhaust valve is of greater diameter than the roller 27 on the other although the shoulders 25 on both are normally in the same relative position so that the arms may not thereby be made non-interchangeable. This increase in diameter is, for the purpose, when desired, of prolonging the period of time during which the exhaust valve is actually unsated thereby providing a further means of regulating the capacity, per cycle, of the exhaust valve and hence the ratio of capacity between the valves. The reason for the effect is that the greater diameter gives a more gradual peripheral curvature which will be engaged earlier by the approaching cam and dropped later than in the case of a small diameter and sharper curvature, as will be readily seen. This result can be attained, however, without in any way interfering with the principles of operation heretofore described, the maximum height to which a controlling member is operated and the consequent distance the valve is actually opened being independent of the diameter of that particular roller, while with the combination of arrangements the flow through a valve is controlled both by the extent to which it is unsated and the

time that it is away from the seat. Of course, for the purposes of this last mentioned adjustment, the roller could be dispensed with and the arm provided instead with a relatively stationary cam contacting the surface of corresponding curvature to that of the roller and of an extent sufficient to traverse the cam during its entire effective movement, such a structure being in effect, produced by considering the rollers of the drawings to be fixed, but this is purely an equivalent arrangement to that provided in the present embodiment wherein the friction is of course greatly reduced.

In the foregoing description, I have, for convenience, described the valve stems 17 as resting at their lower ends upon the shoulders 25 of the controlling members. I prefer, however, not to make these stems continuous and integral, in some instances, but in sections whereby I can provide an additional means of reducing the throw of the intake valve relatively to the exhaust. To this end the lower ends of the stems are made to form separate thrust members 37 and 38, arranged in the guides 20, the member 38 being normally in contact with its stem 17 (both of the latter being of the same length) at 39 so that its action is the same as though positively connected but the member 37 is shorter so as to terminate short of its valve stem and is provided with a recess 40 (Fig. 4) in which operates a plunger 41 having a beaded portion 42 normally held in engagement with the stem by a spring 43 also located in the recess, which spring, however, is lighter than the spring 22 that seats the valve. The member 37, however, is moved by the operating member 24 into co-operation with the head 42 against the tension of spring 43 thus operating the stem 17 through the medium of the plunger by a delayed movement, the lost motion being through the normal distance between the member 43 and the head 42. This lost motion makes the desired change or difference in the operation of the two valves and yet the final engagement is so cushioned by the spring 43 that a sharp and sudden contact is eliminated and consequently the noise and clatter often found in devices of this kind.

The distances between the ends of the portions 17 of the valves and the shoulders 25 are equal and the members 37 and 38 can therefore be readily interchanged for a reversal of the engine in the manner previously described.

I claim as my invention:

1. In a valve mechanism, the combination with a pair of valves, of two interchangeable controlling members operatively connected with said valves respectively, and an actuating device common to both the controlling members, adapted to communicate equal movement to each, one controlling member

being arranged to operate the valve with which it is associated to a greater degree than the other.

2. In a valve mechanism, the combination 5 with a pair of valves, of two interchangeable controlling members operatively connected with said valves, respectively, and a cam device having the same cam surface for actuating both the controlling members in succession adapted to communicate equal movement to each, one controlling member being arranged to operate the valve with which it is associated to a greater degree than the other.
3. In a valve mechanism, the combination 10 with a pair of valves, of two interchangeable controlling members operatively connected with said valves, respectively, and an actuating cam common to both the controlling members for operating them in succession, said cam being symmetrically formed to actuate the members to the same degree and in the same manner but in reverse order when the direction of movement of the cam is reversed, one controlling member being arranged to operate the valve with which it is associated to a greater degree than the other.
4. In a valve mechanism, the combination 15 with a pair of valves, of two interchangeable controlling members operatively connected with said valves respectively and comprising rocker arms and an actuating cam for each arm, the distance between the axis of each arm and the point of connection with its valve being the same, and the distance between the axis of one arm and the effective point of contact with its actuating cam being greater than the corresponding distance on the other.
5. In a valve mechanism, the combination 20 with a pair of valves, of two interchangeable controlling members operatively connected with said valves respectively and comprising rocker arms and an actuating cam common to both arms, the distance between the axis of each arm and the point of connection with its valve being the same, and the distance between the axis of one arm and the effective point of contact with the actuating cam being greater than the corresponding distance on the other.
6. In a valve mechanism, the combination 25 with a pair of valves, of two interchangeable controlling members operatively connected with said valves respectively and comprising rocker arms and an actuating cam common to both the arms for operating them in succession, said cam being symmetrically formed to actuate the arms to the same degree and in the same manner but in reverse order when the direction of movement of the cam is reversed, the distances between the axis of each arm and the point

of connection with its valve being the same 65 and the distance between the axis of one arm and the effective point of contact with the actuating cam being greater than the corresponding distance on the other.

7. In a valve mechanism, the combination 70 with a pair of valves, of operating means therefor comprising a cam shaft and a pair of rocker arms having alined axes and vibrated by successive contact with the same cam surfaces on the cam shaft, said arms 75 being operatively connected with the valve controlling members, respectively.

8. The combination with an engine having a crank case, a cam shaft arranged within the crank case, and a valve mechanism 80 comprising a pair of valves having operating portions extending within the crank case, of valve operating devices comprising a cam shaft having a journal bearing supported by a wall of the crank case, a stud 85 on the wall and a pair of rocker arms journaled on the stud within the crank chamber and vibrated by the cam shaft, said arms being arranged to communicate motion to the operating members respectively. 90

9. In a multiple cylinder engine, the combination with a pair of cylinders, the crank case of each cylinder being separated from that of the adjacent cylinder by a partition, and a valve mechanism comprising a pair of 95 valves for each cylinder, each pair having operating portions extending within the crank case and arranged with their units adjacent to and on opposite sides of the crank case partition, of valve operating 100 mechanism comprising a common cam shaft extending through both crank cases and journaled in the partition and having cam surfaces thereon arranged adjacent to and on opposite sides of the crank case partition, 105 a stud extending through the partition and a pair of rocker arms pivoted on the stud on each side of and adjacent to the partition, said arms being vibrated by contact with the cam surfaces of the cam shaft and arranged 110 to operate the operating portions of the valves.

10. In a valve mechanism, the combination 115 with a pair of valves having operating stems arranged side by side in parallelism, of operating mechanism therefor comprising a pair of interchangeable rocker arms pivoted at a point between the valve stems in the plane thereof and operatively connected thereto, respectively, at points equidistant from their common pivot, and a rotary cam common to both arms and arranged in the plane of the arms to vibrate them successively, and operatively contacting one of them at a point a greater distance from the pivot than the point of contact with the other, said cam being symmetrically formed to operate the arms to 120 125

the same degree and in the same manner, but in reverse order when the direction of the cam is reversed.

11. In an internal combustion engine, the combination with the intake and exhaust valves thereof, of two controlling members operatively connected with said valves respectively, each embodying rollers, the curvature of one roller being greater than that of the other and cam mechanism for vibrating the controlling members through the medium of the rollers, each roller being acted upon by the same cam surface.

12. In a valve mechanism, the combination with a pair of valves, of two controlling members operatively connected with each respectively, and comprising interchangeable rocker arms, a roller on each arm, one of said rollers being of greater diameter than the other and an actuating cam common to both arms and engaging the rollers to vibrate the arms and actuate the valves.

13. In a valve mechanism, the combination with a valve having a stem and a spring for normally holding said valve on its seat, of a thrust member arranged in alinement therewith and provided with a recess, a plunger movable in the recess and having a portion adapted to be engaged by the thrust member, a spring in the recess for holding

the plunger against the valve stem, said spring being lighter than the valve seating spring, and means for successively actuating the thrust member into engagement with the plunger against the action of its spring and operating the valve stem against its seating spring through the medium of the plunger.

14. In an engine, the combination with a pair of valves, of a pair of interchangeable thrust members for operating said valves respectively, one of said members being normally operatively connected with the valve with which it is associated and the other spaced therefrom and an operating cam, 45 common to both thrust members and adapted to operate them successively, said cam being of symmetrical form to present the same cam surface when driven in either of two directions.

15. In an engine, the combination with a pair of valves, of a pair of interchangeable thrust members for operating said valves respectively, one of said members being normally operatively connected with the valve 55 with which it is associated and the other spaced therefrom and a driving element common to both thrust members.
